(57) **CLAIM**

The ornamental design for an electronic device with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of an electronic device with graphical user interface showing the claimed design;

FIG. 2 is a front view of a second embodiment thereof; and, FIG. 3 is a front view of the first embodiment of FIG. 1, shown on an alternate electronic device. The second embodiment of FIG. 2 may be similarly applied thereto.

The outermost broken line showing of an electronic device in FIGS. 1 and 2 forms no part of the claimed design. The broken line showing of an alternate electronic device in FIG. 3 forms no part of the claimed design. The other broken lines in the figures show portions of the graphical user interface that form no part of the claimed design.
